OF MISSOURI.

APPARATUS FOR COUNTING AND PACKING RINGS.

Application filed June 22, 1927. Serial No. 200,719.

This invention relates to apparatus for counting and packing rings such, for example, as rubber fruit jar rings which are formed by slicing a rubber tube to produce a long compact mass of rings arranged in a straight row. The counting is for the purpose of removing groups of rings from the row, each group consisting of a predetermined number of rings.

These rings are usually sold in packages with one dozen rings to a package, and the counting mechanism hereafter referred to can be used to divide the mass of rings into successive groups, each group consisting of twelve or any other desired number of rings. One object of the invention is to produce an automatic machine whereby this counting can be accurately and quickly accomplished.

Another object is to produce a machine whereby the respective groups of rings are positively inserted into packages, such as paper cartons or other containers. In connection with this object attention is directed to the problem of handling a group of flexible rings in such a manner that all of the rings can be quickly inserted into a package only slightly wider than the width of the group of rings. The invention includes means to support and confine the rings while they are passing to the packages, and inserting elements which positively force the rings into the packages. The inserting element preferably lies within the rings, and it preferably enters the packages with the rings, so as to positively force them into the packages. However, this involves the necessity of withdrawing the inserting element from the packages. In the preferred form of the invention, the inserting element lies immediately below the ring-support which does not enter the packages, and after inserting the lower portions of the rings, the inserting element is lifted to lie above the package. The ring-support and inserting element are then quickly withdrawn from the rings, thus allowing the partly inserted rings to drop into the packages.

Another object is to prevent displacement of the end ring in the mass, or row, from which the groups are withdrawn. When a group of rings is picked from the row a stop device preferably follows the group for a slight distance so as to lie in the path of the ring left at the end of the row.

A further object is to produce an improved means for feeding the row of rings to the counting elements which remove the groups from the row.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. 1 is a side elevation of an apparatus embodying the features of this invention, some of the parts being in section on the line 1—1 in Fig. 6.

Fig. 2 is a top view of the apparatus shown by Fig. 1.

Fig. 3 is a top view, on a larger scale, showing one end portion of the trough which supports the stock of rings, and also showing the counting elements adjacent to the trough.

Fig. 4 is a side elevation of the apparatus showing the side opposite to that shown by Fig. 1, some of the parts being in section on the line 4—4 in Fig. 6.

Fig. 5 is an enlarged side elevation showing one end of the trough and the counting elements adjacent to said end.

Fig. 6 is a front elevation of the apparatus.

Fig. 7 is an enlarged side elevation, partly in section, showing the discharge end of the trough and counting elements adjacent thereto.

Fig. 8 is a top view of the discharge end

of the trough showing a stop member adapted to engage the end of the row of rings.

Fig. 9 is a front view of the device shown by Fig. 8, showing the hole through which the rings are discharged, and the stop member at the upper portion of the hole.

Fig. 10 is a side elevation, partly in section, showing the counting elements and inserting elements as they appear when withdrawn from the rings in the package, and latter being shown by dotted lines.

Fig. 11 is a bottom view showing the inserting element in the form of a wing pivoted to the counting element.

Fig. 12 is a detail view of the inserting element.

Fig. 13 is an end view showing the inserting element pivoted to a counting element, the inserting element being elevated relative to said counting element to prevent an unobstructed space for the rings, one of the rings being shown by dot and dash lines.

Fig. 14 is a view similar to Fig. 13, showing the inserting element in a lower position where it may contact with the lower portion of the rings.

Fig. 15 is a vertical section on the line 30 15—15 in Fig. 17, showing the parts in the positions illustrated by Figs. 14 and 17.

Fig. 16 is a section taken approximately on the line 16—16 in Fig. 14.

Fig. 17 is a side elevation of the counting element and inserting element, showing the lower portions of the rings inserted into a carton.

Fig. 18 is a side elevation of a portion of the trough which supports the stock of rings to be counted and packed.

Fig. 19 is an end view of the parts shown in Fig. 18.

Fig. 20 is a section approximately on the line 20—20 in Fig. 18.

Fig. 21 is a section showing portions of the means for lifting and dropping a feed bar at the bottom of the trough.

Fig. 22 is a section showing a lever whereby the feed bar is reciprocated.

Fig. 23 is a view showing the feed bar in its elevated position.

Briefly stated, the apparatus shown by the drawings comprises a horizontal trough holding the stock of rings to be counted and packed, counting elements adapted to receive the end portion of the stock, and a feeder located at the trough to feed the stock to the counting elements. One of the counting elements lies inside of the group of counted rings, and this counting element is carried downwardly to a point above the package which receives the counted rings. The inserting element then enters the package with the lower portions of the rings, so as to positively deliver the rings to the package, and

the inserting element is then lifted and withdrawn from the rings.

The trough used comprises inclined members 1 (Figures 2 and 20), a feed bar 2 provided with ribs 3 adapted to contact with the bottom of the stock of rings, the latter being in the form of a compact row shown by dotted lines at A in Figures 4, 18, 19 and 21. This stock of rings contacts with side members 1 as shown in Fig. 19, but the feed bar 2 can be lifted and moved longitudinally to advance the stock of rings, and then lowered and returned to its starting position.

The means for actuating the feed bar comprises vertically movable bars 4 (Figures 18, 19 and 21) provided with anti-friction rolls 5 at their upper and lower ends, and rotary cams 6 engaging the lower rolls, each of said cams being fixed to a rotary shaft 7. Each vertical bar 4 is mounted in a stationary guide 8 as shown in Fig. 21. The shafts 7 are driven by mechanism hereafter described, so as to rotate the cams 6, thereby lifting and dropping the feed bar 2. The means for imparting longitudinal motion to the feed bar comprises rotary shafts 9 (Figures 1, 20 and 22), each of said shafts being provided with a cam or eccentric 10 located in the forked end of a bell-crank lever 11 (Figures 20 and 22), fulcrumed at 12 and loosely connected at the feed bar by means of a slot and pin connection shown at 13 in Fig. 22. The levers 11 are oscillated to impart longitudinal motion to feed bar 2. When the bar is elevated, it is moved toward the counting device which will be hereafter described, so as to advance the stock of rings, and the bar is then lowered and returned to its starting position.

The end wall of the trough is formed by a flat spacing member 14 (Figures 6, 9 and 10) provided with a hole 15 through which the rings are discharged to the counting elements.

The counting device includes a ring-support 16 adapted to be aligned with the trough, as shown in Fig. 4, so as to receive the rings discharged through the spacing member 14. This ring-support is movable downwardly to deposit the rings into the carton 17, as suggested in Figures 7 and 17. The means for moving the ring-support will be hereafter described.

In addition to the ring-support 16 the counting device includes an abutment, or spacing member, 18 mounted on the ring-support so as to engage one end of the stock of rings which are fed onto said support 16. This support 16 extends from the abutment 18, and its extended portions are approximately equal to the thickness of a group of counted rings. This is suggested by Fig. 17 where the rings are shown at A'. When the ring-support is elevated to receive the rings, its end face lies adjacent to the spacing

member 14 as shown in Fig. 14, and the spacing member 14 then cooperates with the abutment 18 to limit the space for the rings to be counted. In other words, the stock of rings A (Fig. 4) is fed through the spacing member 14 and onto the support 16 while abutment 18 limits the motion of the stock, and the space between this abutment 18 and the spacing member 14 is approximately equal to the thickness of the counted rings. Assuming, for example, that each ring is one eighth of an inch ($\frac{1}{8}$) thick and that it is desired to have twelve rings in each group, the space between the abutment 18 and the spacing member 14 would then be approximately one and one-half inches ($1\frac{1}{2}$).

The ring-support 16 is surrounded by the group of counted rings A', as suggested by Figures 13, 14 and 17, and since this group of rings is confined between the abutment 16 and the spacing member 14, it will be apparent that said rings can be separated from the stock by moving the ring-support 16.

The inserting device cooperates with the ring-support to positively insert the group of rings into the package 17. This inserting device comprises an inserting member in the form of a wing 19 (Figs. 11 to 17) pivoted at 20 to the ring-support and provided with an operating arm 21 having a slot to receive a pin 22 carried by the abutment 18. By means to be hereafter described, abutment is oscillated on the ring-support 16 for the purpose of moving the wing 19 on its pivot 20, said wing being movable from the position shown by Fig. 13 to the extended position shown by Fig. 14. 23 designates a blade extending from one side of the wing 19 (Figures 12, 14 and 17) and cooperating with said wing to insert the rings into the carton. The wing 19 lies within the counted rings, but the blade 23 lies at one side of said rings, as shown in Fig. 17.

When the wing 19 is elevated, as shown in Fig. 13, it does not in any way interfere with the delivery of the rings to the support 16, and said wing occupies this position when the rings are fed onto the support 16. However, when the support 16 is moved downwardly to deliver the rings to the package, the wing 19 is acted upon by mechanism hereafter described so as to move to the position shown in Fig. 14 where it engages the lower portions of the rings, thereby positively forcing said rings into the package, while the blade 23 lies at one side of the rings (Figure 17) to positively locate said side of the rings within the package.

At this time, the closure flap 17 lies at the opposite side of the rings, while the upper portions of the rings are confined between the abutment 18 and the spacing member 14. These conditions, as suggested by Fig. 17, insure a proper delivery of the rings to the package.

Before describing the details of construction, we will state that there is a carrier to raise and lower the ring-support 16 to which the inserting wing 19 is pivoted, and that after the wing 19 enters the package 70 with the rings, said wing is lifted about the axis of its pivot 20 so as to lie above the package, and the support 16 with the wing 19 is withdrawn from the rings, thereby permitting the latter to drop into the package. 75

The carrier just referred to comprises a vertically movable bar 24 slidably mounted in a stationary guide 25 as shown in Figures 1, 6, 7 and 10. This carrier also includes a head 26 at the upper end of the said vertical bar, and various elements supported by said bar and head as will be hereafter described.

The ring-support 16 is formed on one end of a neck 27 (Fig. 16) extending from one end of a square bar 28 which slides horizontally in the head 26. The opposite end of said square bar 28 (Figures 3 and 10) is provided with an extension 29 slidable in a bearing 30 secured to a frame member 31 which is secured to the head 26 as shown in Figures 3 and 7, so as to move vertically with the vertical slide bar 24. The spring 32 surrounding the extension 29 engages a head 33 at the end of said extension and tends to move the ring-support 16 and abutment 18 to the left from the position shown by Figures 3 and 7. However, this movement can be prevented by means of a latch 34 engaging a pin 35 on the square bar 28, as shown in Fig. 7. The latch 34 is pivoted at 36 to the head 26, as shown in Fig. 7, and a spring 37 yieldingly retains the latch in engagement with the pin 35.

It is to be understood that the latch 34 and its spring 37 are carried by the head 26 which moves downwardly with the vertical bar 24, and that the square bar 28 which carried the ring-support 16 also moves downwardly with said bar 24. When these elements reach their lowest positions, the latch 34 is released and the spring 32 then shifts the ring-support 16 and wing 19 to the left from the positions shown in Fig. 17, thereby withdrawing the elements 16 and 19 from the rings. 115

The means for releasing the latch 34 from the pin 35 comprises a finger 38 (Figs. 7 and 10) extending from the latch and adapted to strike a stationary screw 39 immediately before the carrier reaches its lowest position. Fig. 7 shows that the finger 38 is in vertical alinement with the stationary screw 39, and Fig. 10 shows how the finger 38 cooperates with the screw 39 to release 125 the latch from the pin 35.

Immediately after the latch 34 is released, the carrier including the vertical bar 24 moves upwardly in a straight vertical line and a roll 40 (Fig. 10) on the bar 28 travels 130

along a stationary cam 41 with the result of restoring the pin 35 to the latch 34, thereby shifting the ring-support 16 to the right from the position shown in Fig. 10, so when 5 said support reaches its elevated position it lies adjacent to the spacing member 14.

In other words, the ring-support 16 receives the rings while said support lies adjacent to spacing member 14, and the support 10 port 16 then moves downwardly in a straight vertical line to locate the rings in the package 17. When the ring-support 16 reaches its lowest position, the latch 34 is released and the spring 32 then moves said support 15 to the left, locating it in the position shown by Fig. 10. As the carrier rises the roll 40 cooperates with the stationary cam 41 to restore the ring-support 16 to its ring-receiving position, at which time the latch 34 is 20 engaged with the pin 35.

We will now refer to the means whereby the inserting wing 19 is moved upwardly and downwardly relative to the ring-support 16. Briefly stated this is accomplished by oscillating the abutment 18 on the ring-support 16, said abutment being a segmental device provided with a pin 22 engaging the operating arm 21 of the wing 19. The means for turning this abutment in one direction comprises a spring 42 (Figures 16 and 17) coiled around the neck 27 and having one of its ends extended into the abutment 18, the opposite end being extended into the square bar 28. The means for turning said 35 abutment 18 in the opposite direction comprises a stationary finger 43 (Figures 6, 7, 13 and 14) adapted to engage a shoulder 44 on the abutment member 18. After the lower portions of the rings A' have been 40 inserted into the package, the abutment 44 strikes the stationary finger 43, as shown in Fig. 14, and a continued downward motion of the ring holder 16 will cause the abutment 18 to turn on said ring holder, thereby lifting the inserting wing 19 and its blade 23 from the package. Fig. 13 illustrates the position of the wing 19 at the end of this lifting operation.

It is to be understood that the spring 42 50 tends to retain the wing 19 in its extended position shown by Figures 14 and 17, so when the abutment 18 is turned to lift the wing, some means must be provided to retain said wing in its elevated position. To 55 illustrate this feature we have shown a finger 45 extending from the head 26 which moves upwardly and downwardly with the vertical bar 24. The finger 45 is shown by full lines in Fig. 10 and by dotted lines in 60 Fig. 13. The abutment 18 has a shoulder 46 adapted to engage said finger 45 to prevent displacement of the spring-actuated wing 19.

To understand the manner in which the shoulder 46 reaches the finger 45, it should 65 be borne in mind that during one of the

downward travels of the carrier, the shoulder 44 engages the stationary finger 43 for the purpose of lifting the wing 19 to the position shown in Fig. 13, and at this time, the ring-support 16 and abutment 18 are 70 withdrawn from the rings by the action of spring 32, which shifts the elements 16 and 18 to the positions shown in Fig. 10, thereby locating the shoulder 46 at one side of the rigid finger 25, as shown in Figures 10 75 and 13.

However, as the carrier moves upwardly, the ring-support 16 and abutment 18 are moved to the right from the position shown in Fig. 10, this movement being obtained by 80 the action of roller 40 on the stationary cam 41, and it causes the abutment 46 to pass entirely beyond the extended end of the holding finger 45, therefore, another retaining device is employed to prevent release of the spring-actuated member 18 during the upward travel of the carrier.

This other retaining device comprises bar 47 pivoted at 48 adapted to engage a pin 49 on the abutment 18, as shown in Figures 3 85 and 5.

When the action of roller 40 and cam 41 releases the shoulder 46 from finger 45, the pin 49 lies at one side of the extended end 90 of bar 47, and said end and pin 49 then cooperate with each other to prevent release of the spring-actuated abutment 18. Thereafter, while the carrier is moving downwardly, the pin 49 passes from the bar 47 so as to release the abutment 18, thus allowing the spring 27 to shift the wing 19 to the position shown by Figures 14 to 17.

The bar 47 is provided with an adjusting screw 50 which appears in Figures 3, 5 and 10. As the carrier moves upwardly, the head 26 strikes the screw 50 (Fig. 5) thereby causing the bar 47 to move upwardly with the carrier. Said bar 47 is thus retained in engagement with the pin 49 during the final part of the upward motion. When the carrier begins its downward movement, the bar 47 also moves downwardly until it is stopped in the position shown by Fig. 10 by engaging a stationary part of the apparatus.

We will now refer to the stop device which 115 engages the end ring of the stock in the trough when the counted rings are moving downwardly to the package. This stop device is shown in Figures 8, 9 and 10. It comprises an arm 51 pivoted to the spacing member 14, and stop-blade 52 extending from said arm, and a spring 53 tending to force the arm downwardly thereby tending to retain the blade 52 at the end of the stock from which counted rings are removed. A 120 pin 54 extends from the arm 51, as shown in Figures 5, 7, 8 and 10. The extended end of this pin 54 has a head which lies in the path of the abutment 18, and when 125 the carrier moves upwardly, this abutment 130

engages said head, as shown in Fig. 5, so as to remove the stop device from the path of the rings to be fed onto the ring-holder 16. After the rings have been delivered to the 5 ring-holder, the carrier moves downwardly and it is followed by the stop device which locates the blade 52 at the end of the stock from which the counted rings are removed.

The operation of counting and inserting 10 elements will be briefly reviewed as follows.

When the carrier is in its highest position, the inserting wing 19 is elevated to permit free delivery of the rings to the ring-holder 16. At this time the wing 19 is held by the 15 pin 49 cooperating with the bar 47, and the latch 34 then cooperates with the pin 35.

After the rings are delivered to the ring-holder 16, the carrier moves downwardly and the pin 49 passes from the bar 47, thereby 20 releasing the spring-actuated abutment 18, and permitting the spring 42 to turn said abutment for the purpose of shifting the inserting wing 19 to the extended position shown in Fig. 14. The lower portions of 25 the rings are inserted into the package as shown in Fig. 17, while the wing 19 extends downwardly to enter the package with the rings. As this downward movement of the carrier is continued, the wing 19 is lifted 30 while the shoulder 44 strikes the stationary finger 43 as suggested in Figures 13 and 14. The latch 34 (Fig. 7) is released by the co 35 operation of finger 38 and stationary screw 39, and the spring 32 then withdraws the ring-holder 16 and inserting wing 19 from the rings. Shoulder 46 on abutment 18 then cooperates with finger 45 to prevent downward displacement of the wing 19. As the 40 carrier moves upwardly the ring-holder 16 and abutment 18 are shifted through the medium of cam 41 and roll 40, and this releases the shoulder 46 from the finger 45, but the pin 49 then engages the bar 47 to prevent release of the inserting wing 19. 45 The cycle of operations is then repeated.

The packages 17 may be of any desired form and they may be handled in any desired manner. However, it is desirable to cause the packages to travel near the counting and inserting elements, and said packages may be arranged in holders 55 (Fig. 6) 50 pivotally connected together at 56 and adapted to travel between guide bars 57.

The driving mechanism may be of any 55 suitable type, and to illustrate this feature we have shown a power shaft 60 (Fig. 1) provided with a gear wheel 61 meshing with a gear 62 having a crank pin 63 extending into a slot in a lever 64 which is connected to the vertical bar 25 for the purpose of releasing and lowering the carrier.

The means for operating the feeding elements at the trough comprises gear wheels 65 on the cam shafts 7 and gear wheels 66 60 on the eccentric shafts 9. These gear wheels

65 and 66 are driven through the medium of gear wheels 67 on a long shaft 68 provided with a sprocket wheel 69 (Fig. 4) receiving a sprocket chain through which power is transmitted from a sprocket wheel 70 on a shaft 71, the latter having a gear 72 driven by a gear 73 on the power shaft 60.

While the packages 17 are receiving the rings, the closure flaps 17' on said packages are held by engaging the lower margin of 75 the separating members 14, as shown in Figures 7 and 17, and this operating member 14 may be provided with a curved extension 75 as shown in Figures 2 and 8, for the purpose of deflecting the flaps to the desired 80 position.

We claim:

1. In an apparatus for counting rings, a holder for the stock of rings to be counted, a transferring device including a counting 85 member adapted to lie within the counted rings, said transferring device being provided with an abutment limiting the space for rings on said counting member, means whereby said transferring device is moved from a receiving position opposite said holder to a discharge position beyond said holder, and means whereby the stock of rings is intermittently fed from said holder to said counting member. 90

2. In an apparatus for counting rings, a holder for the stock of rings to be counted, a transferring device including a counting member adapted to lie within the counted rings, said transferring device being provided with an abutment limiting the space for rings on said counting member, means whereby said transferring device is moved from a receiving position opposite said holder to a discharge position beyond said holder, and means whereby the stock of rings is intermittently fed from said holder to said counting member, the last mentioned means being effective while the counting member is 105 opposite said holder. 110

3. In an apparatus for counting rings, a trough to support the stock of rings to be counted, a transferring device including a counting member adapted to lie within the counted rings, an abutment on said counting 115 member limiting the space for rings on said member and a vertically movable carrier in which said counting member is slidably mounted, said carrier being movable from a receiving position, wherein said counting member is aligned with said trough, to a discharge position below said receiving position, means whereby said counting member is withdrawn from the rings when the carrier occupies said discharge position, and means 120 whereby the rings to be counted are fed from said trough to said counting member 125 after the carrier reaches said receiving position.

4. In an apparatus for counting and pack- 130

- ing rings, a holder for the stock of rings to be counted and packed, a transferring device movable from a receiving position at said holder to a delivery position at the packages which receive the counted rings, said transferring device including a counting element receiving the rings from said holder and an inserting element whereby the rings are forced into the packages.
5. In an apparatus for counting and packing rings, a holder for the stock of rings to be counted and packed, a transferring device movable from a receiving position at said holder to a delivery position at the packages which receive the counted rings, said transferring device including a counting element receiving the rings from said holder and an inserting element whereby the rings are forced into the packages, said inserting element being movable relative to said counting element so as to move into and out of the packages.
6. In an apparatus for counting and packing rings, a holder for the stock of rings to be counted and packed, a transferring device movable from a receiving position at said holder to a delivery position at the packages which receive the counted rings, said transferring device including a counting element receiving the rings from said holder and an inserting element whereby the rings are forced into the packages, said counting element and inserting element being adapted to lie within the counted rings, said inserting element being below the counting element so as to force the rings into the packages, and means whereby said inserting element is moved upwardly relative to said counting element so as to pass out of the packages.
7. In an apparatus for counting and packing rings, a holder for the stock of rings to be packed a counting element receiving the rings from said holder, an inserting element below said counting element to force the rings into the packages, both of said elements being adapted to lie within the counted rings, a carrier whereby the inserting element and the lower portions of the rings are located within the packages while the counting element is above the packages, said inserting element being movable upwardly relative to said counting element so as to pass out of the packages, and means whereby said elements are withdrawn from the rings at the packages.
8. In an apparatus for packing rings, a holder for the stock of rings to be packed, and a transferring device receiving the rings from said holder, said transferring device being movable from a receiving position at said holder to a delivery position at the packages which receive the rings, said transferring device including an inserting element whereby the rings are positively inserted into the packages.
9. In an apparatus for packing rings, a holder for the stock of rings to be packed, and a transferring device receiving the rings from said holder, said transferring device being movable from a receiving position at said holder to a delivery position at the packages which receive the rings, said transferring device including an inserting element whereby the rings are positively inserted into the packages, said inserting element being adapted to occupy an extended position within the rings so as to enter the packages with the rings, and said inserting element being movable upwardly from said extended position so as to pass out of the packages.
10. In an apparatus for packing rings, a holder for the stock of rings to be packed, and a transferring device receiving the rings from said holder, said transferring device being movable from a receiving position at said holder to a delivery position at the packages which receive the rings, said transferring device including an inserting element whereby the rings are positively inserted into the packages and a ring-support above said inserting element, said ring-support and inserting element being adapted to lie within the rings, said inserting element being extended downwardly from said ring-support to enter the packages with the rings, means whereby said inserting element is moved upwardly relative to said ring support so as to pass out of the packages, and means whereby said support and inserting element are withdrawn from the rings.
11. In an apparatus for packing rings, a holder for the stock of rings to be packed, and a transferring device receiving the rings from said holder, said transferring device being movable from a receiving position at said holder to a delivery position at the packages which receive the rings, said transferring device including an inserting element whereby the rings are positively inserted into the packages, said inserting element including a member adapted to lie within the lower portions of the rings and an extension adapted to engage one side of the rings.
12. In an apparatus for packing rings, a holder for the stock of rings to be packed, and a transferring device receiving the rings from said holder, said transferring device being movable from a receiving position at said holder to a delivery position at the packages which receive the rings, said transferring device including an inserting element whereby the rings are positively inserted into the packages, said inserting element including a member adapted to lie within the lower portions of the rings and an extension adapted to engage one side of the rings, said member and its extension being adapted to enter the packages with the rings, and means

whereby said member and extension are moved upwardly to pass out of the packages.

13. In an apparatus for packing rings, a holder for the stock of rings to be packed, and a transferring device receiving the rings from said holder, said transferring device being movable from a receiving position at said holder to a delivery position at the packages which receive the rings, said transferring device including an inserting element whereby the rings are positively inserted into the packages, and a ring-support above said inserting element, said ring-support and inserting element being adapted to lie within the rings, the inserting element being in the form of a wing adapted to enter the packages and a blade extending from one side of said wing to engage one side of the rings, means whereby said wing and blade are moved upwardly relative to said ring-support so as to pass out of the packages, and means whereby said ring-support, wing and blade are withdrawn from the rings.

14. In an apparatus for counting and packing rings, a trough holding the stock of rings to be counted and packed, a counting device comprising an abutment and a ring-support extending therefrom, means whereby the stock of rings is fed from said trough to said abutment, the abutment being adapted to engage one end of the stock of rings and the ring-support being adapted to lie within the rings, the extended portion of said ring-support being approximately equal in length to the thickness of the counted rings, a spacing member at the discharge end of said trough facing said abutment to limit the space for rings between said abutment and the discharge end of the trough, an inserting device comprising a wing extending from said ring-support and adapted to lie within the counted rings, a carrier whereby said abutment and ring-support are moved to insert the rings into the packages, said wing being adapted to enter the packages with the rings, means cooperating with said carrier to remove the wing from the packages, and means whereby said wing and ring-support are withdrawn from the rings.

15. In an apparatus for counting and packing rings, a trough holding the stock of rings to be counted and packed, a counting device comprising an abutment and a ring-support extending therefrom, means whereby the stock of rings is fed from said trough to said abutment, the abutment being adapted to engage one end of the stock of rings and the ring-support being adapted to lie within the rings, the extended portion of said ring-support being approximately equal in length to the thickness of the counted rings, a spacing member at the discharge end of said trough facing said abutment to limit the space for rings between said abut-

ment and the discharge end of the trough, an inserting device comprising a wing extending from said ring-support and adapted to lie within the counted rings, said wing being pivoted to said ring-support and provided with a blade adapted to engage one side of the counted rings, said abutment being movable relative to said ring-support and operatively connected to said wing so as to move the wing upwardly and downwardly relative to said ring-support, a carrier whereby said abutment and ring-support are moved downwardly to insert the rings into the packages, said wing and blade being adapted to enter the packages with the rings, a stop cooperating with said abutment to remove the wing and blade from the packages, a spring whereby said ring-support, wing and blade are withdrawn from the rings, a latch device preventing displacement of said wing relative to said ring-support, and a tripping device whereby said latch device is released after the counted rings are located on said ring-support.

16. In an apparatus for counting rings, a holder for the stock of rings to be counted, means whereby the rings are fed toward one end of said holder, a counting device receiving the rings from said end of the holder, said counting device including space-forming members providing a space approximately equal to the thickness of the group of counted rings, one of said members being movable to remove the counted rings from said holder for the stock of rings, a stop member arranged at the other space-forming member to engage the end of the stock from which the counted rings are removed, and means for moving said stop member into and out of the path of the stock.

17. In an apparatus for counting rings, a holder for the stock of rings to be counted, means whereby the rings are fed toward one end of said holder, a counting device receiving the rings from said end of the holder, said counting device including space-forming members providing a space approximately equal to the thickness of the group of counted rings, a carrier whereby one of said space-forming members is moved to remove the counted rings from said holder for the stock of rings, a stop member arranged at the other space-forming member to engage the end of the stock from which the counted rings are removed, and means cooperating with said carrier to move said stop member into the path of the stock when the carrier moves away from the stock.

18. In an apparatus for counting rings, a holder for the stock of rings to be counted, means whereby the rings are fed toward one end of said holder, a counting device receiving the rings from said end of the holder, said counting device including space-forming members providing a space approximate-

ly equal to the thickness of the group of counted rings, a carrier whereby one of said space-forming members is moved to remove the counted rings from the holder for the stock of rings, a stop member comprising an arm pivoted to the other space-forming member and a blade extending from said arm, a spring acting on said arm and tending to retain said blade at the end of the stock

from which the counted rings are removed, 10 said arm having an extension engaged by said carrier to remove said blade from the path of the stock of rings.

In testimony that we claim the foregoing we hereunto affix our signatures.

ARTHUR F. THENER.
JOSEPH M. KOUNTZMAN.
